DESIGN FOR A BASE UNIT FOR A CABINET OR SIMILAR ARTICLE

Herbert Morley, Detroit, Lawrence H. Wilson,
Grosse Pointe, and Herbert L. Davies, Detroit,
Mich., assignors to Borg-Warner Corporation,
a corporation of Illinois

Application January 18, 1936, Serial No. 60,661

Term of patent 14 years

To all whom it may concern:

Be it known that we, Herbert Morley, a subject of the King of Great Britain and Northern Ireland and a resident of Detroit, in the county of Wayne and State of Michigan, Lawrence H. Wilson and Herbert L. Davies, the latter two being citizens of the United States and residents of Grosse Pointe and Detroit, respectively, in the county of Wayne and State of Michigan, have invented a new, original, and ornamental Design for a Base Unit for a Cabinet or Similar Article, of which the following is a specification, reference being had to the accompanying drawing constituting a part hereof:

The figure is a perspective view of the base unit for a cabinet, showing our design.

We claim:

The ornamental design for a base unit for a cabinet or similar article, substantially as shown.

HERBERT MORLEY.

LAWRENCE H. WILSON.

HERBERT L. DAVIES.
